UNITED STATES PATENT OFFICE.

CHARLES S. McCARTHY, JR., OF SANDUSKY, OHIO.

DESIGN FOR A CULTIVATOR.

58,195.

Specification for Design.

Patented June 21, 1921.

Application filed January 28, 1920. Serial No. 354,740. Term of patent 14 years.

To all whom it may concern:

Be it known that I, CHARLES S. McCARTHY, Jr., a citizen of the United States, residing at Sandusky, in the county of Erie and State of Ohio, have invented a new, original, and ornamental Design for a Cultivator, of which the following is a specification, reference being had to the accompanying drawing, forming a part thereof, in which—

Figures 1 and 2 are perspective views of a cultivator embodying my design.

I claim:

The ornamental design for a cultivator as shown.

CHARLES S. McCARTHY, JR.
